Inventor
Carl O. Peterson,

By Clarence A. O'Brien, Attorney

UNITED STATES PATENT OFFICE

CARL O. PETERSON, OF ESSEX, IOWA

ALARM SWITCH

Application filed January 21, 1930. Serial No. 422,361.

This invention relates to an improved electrical circuit switch especially adapted for use in automatically controlling an alarm, for instance, a fire alarm.

- 5 More specifically stated, the invention has particular reference to a normally open switch, and an inflammable and fusible means for holding the movable elements of the switch in normally open position.
- 10 In carrying the invention into effect I have found it expedient to accomplish this result by utilizing a box having a spring pressed switch blade arranged therein and held in open position by a fusible trans-
- 15 parent cover.

My principal aim is to generally improve upon appliances of this class by providing one which is characterized by comparative simplicity, durability, practicability, and 20 other features which will fulfil the requirements of an invention of this class in a highly satisfactory manner.

In the drawings:—

Figure 1 is an elevational view of a device constructed in accordance with the present invention.

Figure 2 is a front or face view thereof.

Figure 3 is a cross sectional view showing the switch construction.

30 As seen in Figures 1 and 3 the reference character 4 designates a box or casing of appropriate material and on the open side of this and around the margin I provide an inturned retaining flange 5. Inside of the box is a 35 block mounting 6 carrying a standard 7 on which the blade 8 of the switch is pivotally mounted. The blade is shaped somewhat like a bell crank and includes a blade portion 9 for cooperation with the relatively stationary 40 contact element 10. In addition it includes a handle portion 11 with which one end of spring 12 is connected. The spring is anchored in the box as seen in Figure 1 and 45 serves to press the handle portion of the switch blade 8 outwardly in a manner to force the blade 9 into engagement with the contact element 10. The switch is maintained in open position, however, through the presence of the fusible inflammable laminated cover 50 generally designated by the reference char-

acter 12. This comprises sheet material, the inner sheet or lamination being designated by the numeral 13 and being fastened throughout its marginal portion, as at 14, to the corresponding portion of the outer or top sheet 55 or lamination 15. The free marginal portions of the laminations 13 and 15 embrace the flange 5 therebetween as indicated at 16, thus holding the cover in place. The marginal edge of the outer sheet or lamination 15 is 60 provided with a multiplicity of points, tongues or extensions 17 which project outwardly beyond the box and which serve to become ignited easily and readily in case of fire.

When the cover 12 is in the position seen in Figure 3 it presses against the handle portion 11 of the switch blade 8 thus holding the blade portion 9 disengaged from the contact element 10. As soon, however, as the 70 cover is destroyed by flames from a fire or melted from heat, the spring comes into play and forces the blade 9 into engagement with the contact 10 and closes the circuit. The circuit wires are designated by the numerals 75 18 and 19, respectively, and these are included in an alarm circuit, (not shown).

It is thought that persons skilled in the art to which the invention relates will be able to obtain a clear understanding of the invention after considering the description in connection with the drawings. Therefore, a more lengthy description is regarded as unnecessary.

Minor changes in shape, size and rearrangement of details coming within the field of invention claimed may be resorted to in actual practice if desired.

Having thus described my invention, what I claim as new is:—

1. A circuit closer of the character described comprising a box having an open side, an inturned flange on said open side of the box, a switch mounted in the box, resilient means yieldingly urging the switch toward circuit closing position, and a fusible closure mounted in the open side of the box and engaged with the switch in a manner to retain said switch open position, said cover comprising inner and outer laminations se- 85 90 95 100

cured together adjacent their marginal edges, the free marginal portions of the laminations embracing the flange therebetween in a manner to retain the closure in position on the box.

- 5 2. A circuit closer of the character described comprising a box having an open side, an inturned flange on said open side of the box, a switch mounted in the box, resilient means yieldingly urging the switch toward
10 circuit closing position, and a fusible closure mounted in the open side of the box and engaged with the switch in a manner to retain said switch open position, said cover comprising inner and outer laminations secured
15 together adjacent their marginal edges, the free marginal portions of the laminations embracing the flange therebetween in a manner to retain the closure in position on the box, and integral tongues projecting from the
20 marginal edges of the outer lamination.

In testimony whereof I affix my signature.

CARL O. PETERSON.
